UNITED STATES PATENT OFFICE.

JOHN THOMAS HAVENS, OF ASBURY PARK, NEW JERSEY.

AEROPLANE-GUY-WIRE TIGHTENER.

1,165,168.

Specification of Letters Patent. Patented Dec. 21, 1915.

Application filed July 30, 1915. Serial No. 42,741.

To all whom it may concern:

Be it known that I, JOHN T. HAVENS, a citizen of the United States, and a resident of Asbury Park, in the county of Monmouth and State of New Jersey, have invented a new and Improved Aeroplane-Guy-Wire Tightener, of which the following is a full, clear, and exact description.

This invention relates to aeroplanes and has to deal particularly with a device whereby the guy wires can be quickly tightened or released, the device being of comparatively simple and inexpensive construction, reliable and efficient in use, and so designed as to be applicable to usual forms of aeroplane construction.

A more specific object of the invention is the provision of a connecting device between the vertical struts and the horizontal beams of the aeroplane structures of an aeroplane, such connecting devices having novel means for fastening the guy wires thereto in such a manner that the wires can be quickly and easily tightened or released.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a front view of a portion of an aeroplane frame; Fig. 2 is an enlarged sectional view of a guy wire tightening and releasing device; and Figs. 3 and 4 are horizontal sections respectively on the lines 3—3 and 4—4, Fig. 2.

Referring to the drawing, 1 and 2 designate the upper and lower beams of an aeroplane frame, and 3 the spaced vertical struts. These struts have caps 4 fitted to the ends, and projecting from the caps are threaded studs 5 which pass through the beams 1 and 2 and have nuts 6 for firmly securing the parts together. The frame is stiffened by guy wires 7 disposed in the usual manner, and the ends of the guy wires are formed with loops 8 which are engageable with levers 9 which are fulcrumed at 10 on the inner ends of the caps 4, the free ends of the levers being provided with screw-threads 11, whereby a single nut 12

can lock all the levers on a cap 4 in a position that maintains the guy wires taut. In other words, the nut 12 surrounds the cap 4 and the free ends of the levers are clamped against the outer portion of the cap by the nut 12 or equivalent means which is movable axially on and off the levers when they are substantially parallel with the axis of the cap. To provide for adjustment the levers have adjacent their pivoted ends a plurality of recesses or seats 13 into which the loops 8 of the guy wires 7 can be engaged.

In applying the guy wires the tightening or releasing levers 9 are thrown laterally to a position approximating that shown by dotted lines in the upper right-hand corner of Fig. 1, so that the loops on the guy wires can be passed over the free ends of the levers and slip longitudinally on the latter toward the hinged ends. The loops are engaged in the appropriate seats 13 and then the levers are thrown inwardly against the caps 4, and while so held the clamping ring 12 is screwed on the levers, as shown in Fig. 2. By this arrangement any desired tension may be placed on the guy wires, and furthermore, the guy wires can be easily and quickly attached or detached so as to facilitate the setting up or knocking down of the aeroplane.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A device of the class described comprising a cylindrical body, a plurality of levers spaced around and extending longitudinally of the body and fulcrumed all at the same end of the body, the free ends of the levers having threads, a nut surrounding the body and engaged with the threaded ends of the levers for drawing the latter inwardly against the body, and means on the ful-

crummed ends of the levers for engagement with elements adapted to be tightened by the levers.

2. In an aeroplane, the combination of a 5 strut, a plane beam, a member fitted to the end of the strut, levers fulcrumed on the member at the same end of the latter, guy wires engageable with the levers and adjustable toward and from the fulcrums of the 10 levers, and means holding all the levers in a position to maintain the guy wires under tension.

3. In an aeroplane, the combination of a strut, a plane beam, a member fitted to the 15 end of the strut, levers fulcrumed on the member, guy wires engaged with the levers, and a ring surrounding the member and engageable with the free ends of the levers for holding the latter with the guy wires under 20 tension.

4. In an aeroplane, the combination of a plane beam, a strut fastened thereto, a plurality of guy wires, levers carried by the strut and with which the ends of the guy 25 wires are engageable, and means having a threaded engagement with all the levers to exert a final tension on the guy wires and maintain such tension.

5. In an aeroplane, the combination of a 30 plane beam, a strut fastened thereto, a plurality of guy wires, levers carried by the strut and with which the ends of the guy

wires are engageable, each lever having a plurality of seats arranged respectively at different distances from the fulcrum of the 35 lever for adjustable engagement with the guy wire, and means for holding the levers in approximate parallelism with the strut to maintain the guy wires under tension.

6. A device of the class described comprising a cap, levers fulcrumed on the cap and each having means with which a guy wire may be adjustably engaged, a ring surrounding the cap and arranged to engage the free 40 ends of the levers to hold the same in normal 45 position.

7. A device of the class described comprising a cap, a plurality of levers fulcrumed on the inner end of the cap and swinging in planes passing through the axis of the latter, 50 means on each lever for permitting adjustable connections with a guy wire, and a ring surrounding the cap and engageable with the free ends of the levers for holding the latter 55 approximately parallel with the axis of the cap.

In testimony whereof I have signed my name to this specification in the presence of two subscribing witnesses.

JOHN THOMAS HAVENS.
